LAURENCE P. SAUNDERS, OF LOCKPORT, NEW YORK, ASSIGNOR TO HARRISON RADIATOR CORPORATION, OF LOCKPORT, NEW YORK, A CORPORATION OF NEW YORK

FAN HOUSING

Application filed October 31, 1929. Serial No. 403,844.

This invention relates to an improved cooling system for dissipating heat from an internal combustion engine of the type commonly employed for propelling motor vehicles and the like.

Most motor vehicles in general use today are driven by a multiple cylinder, water cooled engine. The engine cylinders are jacketed for the circulation of water or other cooling medium which takes up the heat of combustion and transfers it to atmosphere, as the water flows through a cooler or radiator connected with the jacket and forming therewith a closed circuit, as is well understood. 5 Air flow past the water passages of the radiator absorbs the heat carried from the engine by the water, and air flow occurs either because of the direct air impact against the front face of the radiator during the higher 10 vehicle speeds or by reason of a forced or induced draft created by an engine driven fan at lower vehicle speeds and engine idling periods.

It has been found that the air flow due to direct impact is directly proportional to vehicle speed while fan draft varies with the vehicle and engine speed, being greater than impact in the lower speed range and materially less throughout the higher speed range, 15 decreasing in relative value as speed increases. Observation of standard cars on the market has shown that, depending upon equipment used, fan blast is of a value greater than impact up to a point from between 35 to 50 miles per hour. Beyond that the force of impact greatly exceeds fan draft and the fan becomes a negligible factor and its need is practically eliminated. In some cases the fan may be driven through an automatic 20 clutching device whereby its action ceases beyond a predetermined speed. It will be obvious of course, that the faster the engine is driven, the more heat there is to be dissipated, and therefore, a sufficient amount of 25 radiating surface must be provided to main-

tain a proper engine operating temperature at times of greatest heat generation.

It follows that the radiating area to fit some conditions may not fit others and to provide a cooling system that will the more nearly meet varying conditions is one of the primary objects of the present invention. 50

To this end there is contemplated the provision of a radiator and a fan with which is associated a shroud or hood surrounding the fan and covering a portion of the radiator to concentrate and confine the action of the fan blast to a fractional portion of the total radiating surface. 55

As a result of the shroud the full value of fan blast is available for circulating air through the shroud covered portion during such times as when there is little or no impact air flow and when the whole of the radiator is not needed to extract heat generated. 60 Furthermore, since all the air set in motion by the fan must pass through the radiator because of the shroud, use may be made of a fan smaller in size than would ordinarily be the case and this lessens manufacturing costs, 65 reduces weight and lowers power consumption. The shroud covers only so much of the radiating area as is needed to dissipate the heat generated at the lower speeds. Upon increased heat generation as the engine speed and vehicle travel increases, the uncovered portion of the radiator comes into action because of the impact and the greater the speed the greater the impact and, therefore, the 70 more heat given off. In other words, when the movement of the vehicle is slow, only that portion of the radiator acted upon by fan blast, is effective and necessary to transfer the heat, and when vehicle movement and heat 75 generation is more rapid the whole of the radiator becomes effective to a degree dependent upon the rate of speed. In this fashion the operating temperature of the engine may be maintained substantially constant or uni- 80 85 90

form throughout the entire speed range of the vehicle.

The invention and its various features of advantage will be better comprehended upon reference to the accompanying drawings when taken in connection with the following description:

In the drawings—

Figure 1 is a side elevation of an engine shown in outline and a radiator therefor, illustrating an application of the invention, parts being broken away and shown in section.

Figure 2 is a rear elevation of the radiator shown in Figure 1.

Figure 3 is a view similar to Figure 1 and in which is embodied a slight modification.

Figure 4 is a rear elevation of the radiator shown in Figure 3.

Referring to the drawings, reference numeral 1 indicates an internal combustion engine, the water jacket of which is provided with an inlet 3 and an outlet 4. In front of the engine is shown a cooler or radiator which, according to conventional construction may consist of a pair of spaced headers or tanks 6 and 7 having therebetween a radiating unit or core 8 of either the tubular type or of cellular formation, the latter usually comprising a series of thin plates secured together in spaced pairs to form a number of vertical water passages connecting the upper and lower tanks with horizontal air spaces therebetween. An ornamental shell or casing 9 may be used to surround the radiator structure to lend to it an improved appearance. From the upper tank 6 a filler spout 10 extends through the ornamental shell 9 and is closed by a removable cap 11. Extending rearwardly from the upper tank is shown an inlet pipe 13 connected through the hose 14 with the outlet 4 of the engine. A similar hose connection 15 communicates the outlet 16 of the lower tank 7 with the inlet tube 3 of the engine thus enabling a complete circulation of the cooling liquid from the engine to the radiator and back to the engine.

Mounted upon the forward portion of the engine directly behind the radiator is a rotating fan 18 which may be driven through a suitable pulley belt from an engine shaft to draw air through the radiator core. A shroud or hood 19 surrounds the fan and covers the lower portion of the radiating core to confine the action of the fan blast on such covered fractional portion of the total radiating surface of the core. This shroud may be secured in place as by riveting, bolting or otherwise to a series of ears 20 extending rearwardly from the radiator structure.

From the above description it will be apparent that the force of the fan is concentrated on the covered fractional portion of the core, so that at low speeds only that portion of the core will be effective through

which air is being drawn. That portion of the core above or beyond the shroud being uncovered at both front and rear, permits free flow of air therethrough due to impact alone. Thus at the higher speeds, not only is the lower portion of the radiator active in dissipating the heat but the entire radiating area is utilized.

The arrangement shown in Figures 3 and 4 is substantially the same as that previously described with the addition of an apertured plate 21, positioned over that portion of the core beyond the shroud. The central upper portion of the plate 21 is depressed as at 22 to clear the inlet pipe 13. Deflector fins or louvres 23 may be provided at the several apertures in the plate 21 in order to deflect the air flowing through the upper portion of the radiator downward from whence it flows around the engine and out beneath the body in the usual fashion.

While the invention has been described more or less specifically it is to be understood that it is not limited to the exact details shown and that such modifications may be made as come within the scope of appended claims.

I claim:

1. In combination, a radiator, an air circulating fan, and a shroud surrounding the fan adapted to confine fan blast to a fractional portion only of the radiating area.
2. In a motor vehicle having an internal combustion engine of the water cooled type, a radiator forming a part of the engine cooling system adapted to dissipate heat to the impacted air stream at high vehicle speeds throughout its entire area, an engine driven fan adapted to induce an air stream through the radiator, and a fan shroud covering a fractional portion of the radiating area to concentrate the fan induced stream on such portion.
3. In combination, a radiator having spaces therethrough for air flow with part of the spaces uncovered on both sides of the radiator, a shroud covering other spaces on one side, and a fan associated with the shroud for creating air flow through the spaces covered by the shroud.
4. In combination, a radiator having spaces therethrough for air flow, a fan for creating an air draft and a shroud surrounding the fan and associated with a fractional portion only of the total number of air spaces, and an apertured member associated with the remaining air spaces.
5. In combination, a radiator having spaces therethrough for air flow, a fan for creating an air draft and a shroud surrounding the fan and associated with a fractional portion only of the total number of air spaces, and an apertured member associated with the remaining air spaces, and having air deflecting louvers adjacent the apertures.
6. In a cooling system for motor vehicle

engines, a radiator having its entire heat radiating surface exposed for the flow there-against of impacted air upon vehicle travel, and means to increase air flow above that
5 incident to impact in the lower vehicle speed range against a portion of the radiating sur-
face, including an air flow passage communi-
cating with a fractional portion only of the
entire radiating surface and means to induce
10 air flow through said passage.

In testimony whereof I affix my signature.
LAURENCE P. SAUNDERS.
